(57) **CLAIM**

The ornamental design for the display screen or portion thereof with graphical user interface, as shown and described.

DESCRIPTION

FIG. 1 is a front view of a display screen or portion thereof with graphical user interface showing our new design; and, FIG. 2 is an alternative embodiment thereof.

The broken line showing of the display screen forms no part of the claimed design. The broken line showing within the graphical user interface forms a part of the claimed design.
